ATTORNEY.

UNITED STATES PATENT OFFICE

136,361

DESIGN FOR A CASE FOR GLASSES

Phillip S. Sockett, Los Angeles, Calif.

Application July 19, 1943, Serial No. 110,708

Term of patent 14 years

To all whom it may concern:

Be it known that I, Phillip S. Sockett, a citizen of the United States, residing at Los Angeles, in the county of Los Angeles, State of California, have invented a new, original, and ornamental Design for a Case for Glasses, of which the following is a specification, reference being had to the accompanying drawing, forming part thereof.

Fig. 1 is a front perspective view of a case for glasses, showing my new design.

Fig. 2 is a rear view thereof.

I claim:

The ornamental design for a case for glasses, substantially as shown.

PHILLIP S. SOCKETT.
